UNITED STATES PATENT OFFICE.

ZOUAVE S. RANDLEMAN AND MARTIN C. RANDLEMAN, OF CARLISLE, IOWA.

ADJUSTABLE TONGS, &c.

SPECIFICATION forming part of Letters Patent No. 519,774, dated May 15, 1894.

Application filed October 6, 1893. Serial No. 487,403. (No model.)

To all whom it may concern:

Be it known that we, ZOUAVE S. RANDLEMAN and MARTIN C. RANDLEMAN, citizens of the United States of America, residing at Carlisle, in the county of Warren and State of Iowa, have invented an Improved Adjustable Tong, Wrench, and Vise, of which the following is a specification.

The object of our invention is to provide 10 a simple, cheap, and durable device adapted for use by blacksmiths as a pair of tongs, or for use as a wrench, or vise and which may be readily set to a position approximately corresponding in size to the object to be grasped, 15 and then made to firmly engage said object by bringing the handles thereof together.

Our invention consists in details in the construction, arrangement and combination of the parts of the device, as hereinafter set 20 forth, pointed out in our claims, and illustrated in the accompanying drawings, in which—

Figure 1 is a view of the complete device with the jaws shown extended by dotted lines. 25 Fig. 2 is an edge view of the same. Fig. 3 is a view of the device adapted for use as a vise, and applied to a bench.

Referring to the accompanying drawings the reference letter A is used to designate 30 the stationary handle having its outer end A² bent at right angles and a jaw A³ formed thereon, said jaw having an angular opening formed therein in proximity to, and parallel with, the part A.

35 B designates the sliding jaw of about the same size and shape as the jaw A³ and having a rack B² formed on its inner end to enter the said opening in the part A³.

C designates the movable handle, pivotally 40 mounted in the outer end of the part A² beyond the jaw A³ and having its end pointed at C² to engage the rack B². The teeth of said rack and the end of said movable handle are so arranged relative to each other, that

45 when the handle is swung outwardly away from the stationary handle a sufficient distance, the rack will not engage it, thereby allowing the movable jaw to be adjusted relative to the other one, and when the handles 50 are brought together, the end of said movable

handle will engage said rack and when moved farther will bring said jaws forcibly together.

D is a pin extended transversely through the outer end of said rack with its ends projecting laterally beyond the face thereof to 55 engage the sides of the opening in the jaw A³ and prevent the movable jaw from being entirely removed.

In adapting the device for use as a vise, we prefer to employ the following mechanism: F, F, designate clips secured to the side of a suitable bench F² to receive the stationary handle and firmly hold it in place.

H designates a lever fulcrumed to a suitable part of the bench to serve as a treadle 65 and H² a rope fixed thereto passed over a direction pulley H³ and attached to the movable handle, so that a downward pressure upon the treadle will bring the jaws together.

J is a segmental rack adapted to be engaged by a pawl fixed to the said treadle 70 hold it in any position and thereby hold the jaws together.

It is obvious that the jaws may be serrated or toothed, as shown in Fig. 3, and adapted to 75 grip a round rod or tube as well as angular objects.

Having thus described our invention, what we claim as new therein, and desire to secure by Letters Patent of the United States there- 80 for, is—

1. An improved tong, comprising a handle A, having a portion A² bent at right angles thereto and terminating in a bearing as shown, a jaw A³ projecting outwardly from 85 the part A², a jaw B in the same plane as the jaw A³ and provided with a rack B² bent at right angles to the jaw and extended through a slot in the base of the jaw A³, a lever C pivoted in the bearing on the part A² 90 as set forth, and having its end C² adapted to engage the rack B², all arranged and combined, substantially as, and for the purposes, stated.

2. An adjustable tong, for holding small 95 and large objects, composed of three parts, to wit: a handle that has a right-angled bend terminating in a bearer for a mating handle, a fixed jaw extended forward from said right-angled bend and provided with an opening 100

at its rear end, a mating jaw that has an arm extending at right angles from its rear end detachably and adjustably connected with the fixed jaw and the rear face and free end 5 portion of said arm notched, and a mating handle pivoted to the bearer at the end of the right angled part of the handle having the fixed jaw to engage the notched part of

the arm extending from the sliding jaw, to operate in the manner set forth.

ZOUAVE S. RANDLEMAN.
MARTIN C. RANDLEMAN.
